QUILL NOZZLE

Frank B. Downing, Sr., Wilkes-Barre, Pa.

Application November 17, 1941, Serial No. 419,509

2 Claims. (Cl. 57—138)

This invention relates to a quill nozzle and has for one of its objects the production of a simple and efficient nozzle for forming wire rope and preforming the strands in a manner to cause the strands to fit snugly together when the rope is formed or twisted.

A further object of this invention is the production of a simple and efficient nozzle wherein the quills which preform the wire strands rest in formed channels or beds and are firmly secured in position and in parallel relation.

Other objects and advantages of the present invention will appear throughout the following specification and claims.

In the drawing—

Figure 1 is an end elevational view of the quill nozzle;

Figure 2 is a longitudinal sectional view taken on line 2—2 of Figure 1;

Figure 3 is a fragmentary sectional view taken on line 3—3 of Figure 2;

Figure 4 is a sectional view taken on line 4—4 of Figure 3;

Figure 5 is a fragmentary top plan view of a portion of the nozzle showing one of the quills in position.

By referring to the drawing, it will be seen that 10 designates the center portion of the nozzle which is provided upon the periphery thereof with longitudinally extending spaced parallel channels 11, substantially circular in cross-section. Elongated quills 12, circular in cross-section, fit in the formed channels 11 so as to lie longitudinally of the channels 11, as shown. These quills 12 are provided with strand-receiving spiral grooves 13 formed in the periphery thereof which spirally extend longitudinally from end to end of the quills 12 for preforming the strands 14. The spiral groove 13 of each quill 12 makes one complete turn around the quill 12, as shown. These quills 12 are anchored in position against independent rotation or independent longitudinal movement relative to the head 10 by means of countersunk screws 15 which extend transversely through the quills 12 and into the head or center portion of the nozzle 10, as shown. The ends of the quills are beveled and project slightly beyond the ends of the head 10, note Figure 2.

Filler wire quills 12^a of smaller diameter than the quills 12 are placed within formed sockets or channels arranged in the center portion 10, as shown in Figure 1, and these filler wire quills 12^a are interposed between the quills 12. The quills 12^a are similar in construction to the quills

12 with the exception that they are of smaller diameter and these quills 12^a are provided with spiral channels 13^a similar to the channels 13.

The quills 12^a are anchored in position by means of threaded screws 15^a indicated in Figure 3. It should be understood that in place of the screws which are illustrated as holding the quills in position, pins of any character may be employed which pass through the quills and fit into suitable sockets formed in the center portion 10.

In place of the screws 19, suitable pins may be substituted therefor, if desired, for anchoring the quills 18 in position.

15 An outer sleeve 16 fits over the head 10, and this sleeve 16 is provided with a plurality of longitudinally extending spaced formed channels 17 similar to the channels 11. These channels 17 are formed in the outer periphery of the sleeve 16 and the channels 17 are preferably substantially circular in cross-section, as shown. Quills 18 are fitted into the channels 17 and are anchored in position by means of the countersunk screws 19. The quills 18 are provided with longitudinal spiral grooves 20 similar to the grooves 13 formed in the quills 12. This sleeve 16 may be anchored to the head 10 in any desired manner, such for instance as by means of a key, if desired. A retaining casing sleeve 21 fits over the sleeve 16 and is held in position by means of a suitable countersunk screw 22.

Any number of sleeves 16 may be fitted one upon the other if desired, to form a wire rope of a desired number of preformed strands without departing from the spirit of the invention. An important feature of the invention is the fact that the sleeve 16 may be detached and removed from the head 10 by sliding the same off the end of the head 10 and the quills 18 may be individually removed for replacement or to facilitate access to the wires or strands which are being preformed. By removing the screws 15 the quills 12 may be individually removed after the sleeve 16 and the casing sleeve 21 are removed. The quills 18 may be individually and selectively removed by simply removing the screws 19 which hold the quills 18 in place. The quills 12 and 18, as well as the sleeve 16, may be of suitable length to suit the length of rope or cable desired.

As shown in Figure 1, the casing sleeve 21 may be formed in a pair of sections which are slightly spaced as at 21^a to permit lubricating oil to pass in between the sections of the sleeve 21 and to ultimately enter the spiral grooves 20.

The quills may be arranged for a right and a left lay rope. Because of the structure illustrated and described, it will be seen that the quills may be easily removed to repair the strands or to replace the same, and access may be easily had to the inner quills 12 by removing the sleeve 16 and casing sleeve 21. It should be understood that the nozzle may be used without or with the sleeve 16, or as many sleeves may be used as desired, a suitable casing sleeve 21 of suitable size 10 being used to fit the desired diameter.

It should be understood that certain detail changes may be made without departing from the spirit of the invention, so long as such changes fall within the scope of the appended claims. 15

Having described the invention, what I claim as new is:

1. A quill nozzle of the class described comprising a head having a channel extending longitudinally of the periphery of said head, a quill fitted in said channel, an anchoring element extending transversely through said quill and into 20

said periphery for anchoring the quill in a set position against independent rotation and independent longitudinal movement upon said head, and an encasing means surrounding the head and covering the quill and channel and overlying the anchoring element for preventing the accidental removal of the anchoring element while the encasing means is in place.

2. A quill nozzle of the class described comprising a head having a plurality of spaced longitudinal channels in the periphery of the head, a quill fitted in each channel, an anchoring pin fitting transversely through each quill and engaging the head for holding the quills against independent rotary and longitudinal movement relative to said head, and an encasing element snugly fitting around the periphery of said head and encasing the channels and quills and also encasing the anchoring pins for preventing accidental removal of the anchoring pins while the encasing element is in place.

FRANK B. DOWNING, SR.
